UNITED STATES PATENT OFFICE

2,654,429

KNIFE CONTROL FOR PAPER-CUTTING MACHINES

William C. Rupp, Parma, Ohio, assignor to The Chandler & Price Company, Cleveland, Ohio, a corporation of Ohio

Application October 27, 1949, Serial No. 123,865

7 Claims. (Cl. 164—52)

1

This invention relates as indicated to a knife control for paper cutting machines and, more particularly, to a knife control for power operated paper cutting machines also having a power operated binder clamp adapted firmly to clamp a stack of sheets or the like upon the table of the cutter.

In my co-pending application Serial No. 60,341, filed November 16, 1948, I disclose an improved power operated binder clamp which is much more rapid and efficient in operation than the common hand clamp means. In my co-pending application Serial No. 112,659, filed August 27, 1949, I disclose certain improved driving mechanism for the reciprocating knife commonly employed in such machines. The present invention relates to novel control means interrelating the operation of the binder clamp with the knife actuating mechanism, and reference may be had to the two foregoing applications for a description of the other features of the machine in which I prefer to incorporate such newly improved control means. It will be understood, however, that such control means may be employed in paper cutting machines generally, including those illustrated and described in Tyler et al. Patent No. 1,967,600 and Reichart et al. Patent No. 2,305,735.

In such machines a flywheel driven by an electric motor may be connected through a clutch with a crank adapted to reciprocate the knife to cut a stack of sheets or the like. Generally, a bed or table is provided upon which the stack of sheets may be precisely positioned by means of adjustable gauges, and a vertically reciprocable knife is drawn down to make the cut and again elevated by means of such power driven crank. Means will also desirably be provided to prevent accidental actuation of the knife and to insure that the knife will return to fully elevated position after completion of a cut and remain there without repetition of the cycle. It is also highly important that the binder clamp be brought down into firm clamping engagement with the stack upon the table prior to bringing down the knife to cut or trim such stack. It is with such latter aspect that the present invention is concerned.

It is accordingly a primary object of my invention to provide knife control means for paper cutting machines and the like operative to permit operation of such knife only after the material to be cut has been firmly clamped.

A further object of my invention is to provide control means of the type indicated which will

2

be positively actuated and equally effective without adjustment regardless of the thickness of the stack on the table.

Still another object is to provide means effective to prevent manual actuation of the knife drive means until the stack has thus been firmly clamped.

Other objects of this invention will become apparent as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a front elevational view of a paper cutting machine embodying my invention;

Fig. 2 is a fragmentary sectional view through the binder clamp of such machine taken along the line 2—2 on Fig. 1; and

Fig. 3 is a front elevational view generally similar to Fig. 1 but illustrating a different embodiment of the invention.

Referring now more particularly to said drawing, my new control means may be incorporated in a paper cutting machine of generally conventional construction comprising a base frame 1 carrying a bed or table 2 upon which a stack of sheets may be positioned to be cut. A back gauge 3 may be adjusted forwardly or rearwardly of table 2 by means of hand wheel 4, the position of such gauge being indicated by a traveling steel tape in window 5 as described in Reichart et al. Patent No. 2,203,547. A knife bar 6 carrying knife 7 is mounted for generally vertical reciprocation in upper frame 8, a wooden knife stick 9 being inset in the upper surface of the table to avoid possible damage to the knife.

The knife bar 6 and knife 7 are adapted thus to be reciprocated by means of a connecting rod 10, crank 11 and crankshaft 12 driven through a clutch from a flywheel driven by an electric motor (not shown). Such clutch for engaging and disengaging the flywheel is adapted to be actuated by a hand lever 13 preferably of the safety type such as that requiring the same to be first moved to the right and then to the left as viewed in Fig. 1 to cause engagement of the clutch to reciprocate the knife bar. When one cycle of operation has been completed, the clutch will be automatically kicked out and the brake (also

not shown) applied, leaving the knife in elevated position.

Back gauge 3 may be shifted back and forth as desired by means of hand wheel 4 and locked in adjusted position by locking lever 14.

Referring now also to Fig. 2 of the drawing, the binder clamp there illustrated comprises the usual presser foot 15 extending transversely of table 2 and guided for vertical movement in conventional manner by the side frame members. 10 Such presser foot is carried by a vertically extending screw 16 threadedly engaging nut 17 which is locked against rotation by means of set screw 18. Screw 16 may be driven by a reversible electric torque motor (not shown) through shaft 19 and speed reducing gears 20 and 21. Gear 21 is adapted to turn freely on upper end portion of shaft or spindle 22 constituting the upper extension of screw 16 and rests upon a collar 23 carried by such spindle. Collar 23 in turn 20 normally rests upon the upper surface of bearing 24 and another collar 25 is secured to spindle 22 at a point normally slightly (about $\frac{1}{8}$ inch) below the lower end of such bearing.

A twin disc friction clutch of well-known conventional construction is carried by the upper end of spindle 22 for connecting gear 21 in driving connection with such spindle. Such clutch includes a plurality of interleaved driving plates within a casing 26, alternate plates being secured to spindle 22 and gear 21. Nut 27 may be adjusted to force steel back-up plate 28 against rubber compression member 29 to regulate the friction developed within such clutch. Consequently, the force with which the binder clamp presses down upon the stack of sheets may be varied as desired.

Hand lever 13 is keyed to a rock shaft 30, oscillation of which is operative to control the knife drive mechanism in conventional fashion as above explained. A dog 31 is likewise keyed to shaft 30 and is adapted to engage the plunger or armature 32 of solenoid 33 when lever 13 is in clutch-disengaging and brake-applying position. A stop bracket 34 supports plunger 32, preventing movement of lever 13 to the left as viewed in Fig. 1 when such plunger is advanced. It will accordingly be apparent that it is physically impossible for the operator of the machine to actuate the knife until such solenoid plunger has been retracted.

A normally open limit switch 35 is mounted within upper gear housing 36 with a lower contact provided with a roller 37 adapted to engage the upper margin of the outer periphery of gear 21. As shown in Fig. 1, such switch is connected in an electric circuit with solenoid 33 so that when the switch is closed the solenoid will be energized to retract plunger 32 from the path of dog 31, permitting the latter to be rocked in a counterclockwise direction as viewed in Fig. 1.

After a stack of sheets has been properly positioned on table 2 against back gauge 3, the operator first moves hand lever 13 to the right as viewed in Fig. 1, thereby operating micro-switch 38, completing a circuit energizing the electric motor (not shown) driving shaft 19. The spindle 22 is thereby revolved through the action of gear 21 and the clutch means carried by the upper end of such spindle to turn screw 16 to move presser foot 15 downwardly into clamping engagement with such stack. As above explained, the degree of pressure imposed upon the stack will depend upon the adjustment of nut 27. When presser foot 15 can no longer move downwardly, con-

tinued rotation of screw 16 will cause spindle 22 to rise the distance permitted by collar 25, carrying with it gear 21. Elevation of such gear operates micro-switch 35 to complete the circuit energizing solenoid 33 and retracting plunger 32. Such latter circuit may, if desired, also include electric signal means such as a red lamp or the like to indicate to the operator that the stack has been firmly clamped.

The operator may now move the hand lever to the left as viewed in Fig. 1 to engage the clutch (not shown) of the knife drive mechanism and disengage the brake (see my above-identified application Serial No. 60,341). Crankshaft 12 accordingly is turned to reciprocate connecting rod 10 and likewise reciprocate knife bar 6 and knife 7 to make the cut. Upon completion of this cycle, lever 13 is automatically rocked in a clockwise direction back into starting position as shown in Fig. 1 and the knife drive clutch disengaged and the brake reapplied.

A cam 39 turning with crankshaft 12 is adapted to operate a micro-switch 40 upon return of the knife to its uppermost position, reversing the binder clamp motor to turn screw 16 in the opposite direction to elevate presser foot 15. When such presser foot is thus elevated, gear 21 is of course permitted to drop down with consequent opening of micro-switch 35 and de-energization of solenoid 33. Solenoid plunger 32 thereupon again drops down into position between dog 31 and stop 34. When the binder clamp reaches fully elevated position, it will engage and operate limit switch 41, stopping the binder clamp motor. A new stack of sheets may now be placed upon the table and the cycle repeated.

It will be apparent from the foregoing that I have provided novel knife control means rendering it impossible to actuate the knife until the binder clamp is firmly pressing upon the stack of sheets to be cut. An additional manually operable switch may be provided, if desired, to close the solenoid operating circuit so that the knife may then be brought down for the purpose of adjustment or the like without at the same time operating the binder clamp. The binder clamp motor will be turned off under such circumstances.

Not only will engagement of the knife with the stack prior to clamping of the latter be prevented but also a further safety factor is provided for the operator who cannot bring down the knife accidentally while he is arranging the stack on the table. While the mechanism is simple and inexpensive, it is nevertheless positive in operation, the rotation of screw 16 serving first to lower the clamp and then to elevate the spindle. Various forms of guard means, including any suitable latch or lock, may be employed instead of solenoid plunger 32 and while electrical control of such means is preferred it will be obvious that equivalent mechanical devices, such as link and lever means may be used to actuate such guard means in response to lifting of the binder clamp screw. A principal feature of this embodiment of my invention is the arrangement whereby such screw is caused to rise when the stack is firmly clamped and thereby release the means normally preventing operation of the knife drive mechanism. In other words, the stack clamping pressure is itself utilized to actuate the knife drive control means.

Referring now to Fig. 3 of the drawing, the embodiment of my invention there illustrated operates on the same general principle above

explained. Instead of binder clamp screw 16, however, a double acting fluid pressure piston-cylinder assembly 42 is provided mounted vertically in head frame 8, an extension 43 of such piston engaging and supporting binder clamp presser shoe 15. The usual fluid pressure supply lines 44 and 45 are adapted to conduct such fluid (ordinarily hydraulic, although air pressure may be employed) to the upper and lower ends of said cylinder respectively. A branch line 46 leads to the lower end of fluid pressure cylinder 47, so that pressure in such line acts to retract plunger 48. Plunger 48 corresponds to armature 32, being interposed between dog 31 and stop 34, and normally held in extended position by action of compression spring 49. Thus, when fluid pressure is admitted to line 44 and relieved from line 45 by any suitable valving means, then presser shoe 15 will be brought down in clamping engagement upon the stack or table. Pressure is thereupon built up in line 46 sufficient to overbalance spring 49 and retract plunger 48, whereupon lever 13 may now be shifted to operate the knife drive mechanism. When line 44 is connected to drain and line 45 to pressure the presser foot 15 will be elevated and spring 49 will again be effective to interpose stop plunger 48.

It will be appreciated that control means of the type above described are particularly advantageous where movement of the binder clamp is slower than movement of the knife. When a screw feed for the clamp is employed, the less the pitch, the less the power required to obtain a desired clamping pressure. Similarly, when employing hydraulic means, the slower the piston moves, the lower the capacity of the pump required to supply the fluid under pressure. It is most important that the more rapidly traveling knife should not start its downward movement until the stack has actually been firmly clamped. Provision of an arbitrary time-delay means of well-known type is not a satisfactory solution to the problem under these circumstances since the stack to be cut may be of varying thickness and the time-delay interval allowed would always have to be sufficient to permit the clamp to travel all the way to the table in order to be safe. With my novel arrangement the knife may be actuated promptly just as soon as the stack has been clamped, whatever may be the height of such stack. Furthermore, the knife may be brought down rapidly to obtain desired cutting characteristics without any danger of engaging the stack prematurely prior to proper clamping of the latter. These advantages I achieve by making operation of the knife drive mechanism dependent upon first obtaining clamping pressure on the stack.

Other modes of applying the principle of the invention may be employed, change being made as regards the details described, provided the features stated in any of the following claims or the equivalent of such be employed.

I therefore particularly point out and distinctly claim as my invention:

1. In a power driven paper cutting machine including a knife, a crankshaft adapted when rotated to reciprocate such knife, and a hand lever adapted to be rocked to actuate such crankshaft and knife; the combination of a binder clamp adapted to clamp a stack of sheets or the like upon the table of such machine prior to actuation of such knife, said binder clamp comprising a vertically disposed spindle, a screw on the lower end of said spindle, a presser foot

adapted to bear upon such stack threadedly engaging said screw for vertical reciprocation when said screw is rotated, a gear supported on the upper portion of said spindle for free rotation relative thereto, a disc-type friction clutch on said spindle interconnecting said gear and spindle in driving connection, a nut threaded on the upper end of said spindle adapted when tightened to increase the frictional resistance of said clutch, whereby the downward thrust of said presser foot upon such stack may be regulated, means operative to drive said gear, a rock shaft adapted to be rocked by such lever to actuate such crankshaft and knife, a dog secured to said shaft for oscillation therewith, a solenoid having an armature adapted when extended to engage said dog to prevent rocking of such lever to actuate such knife, a back-up stop adapted to support said armature against movement by said dog, an electric circuit controlling said solenoid, a normally open limit switch in said circuit located above said gear and adapted to be closed to energize said solenoid to retract said armature to permit rocking of such lever to actuate such knife when continued rotation of said screw after engagement of said presser foot with such stack operates to elevate said spindle, and means limiting such elevation of said spindle.

2. In a power driven paper cutting machine including a knife adapted to be reciprocated to make a cut, and a hand lever adapted to be rocked to actuate drive mechanism for reciprocating such knife; a binder clamp adapted to clamp a stack of sheets or the like upon the table of such machine comprising a vertically disposed spindle, a screw on the lower portion of said spindle, a presser foot adapted to bear upon such stack threadedly engaging said screw for vertical reciprocation when said spindle and screw are rotated, a gear carried by the upper portion of said spindle freely rotatable relative thereto, clutch means on such upper portion frictionally interconnecting said gear and spindle in driving connection, means adjustable to vary the degree of friction developed in such clutch thereby to regulate the downward thrust of said presser foot upon such stack, means operative to drive said gear, a back-up stop, means rigid with such lever and rockable therewith, a solenoid having an armature adapted when extended to be interposed between said last-named means and said back-up stop to prevent rocking of such lever to actuate such knife, an electric circuit controlling said solenoid, a normally open switch in said circuit positioned to be operated by lifting of said spindle, and means limiting the distance said spindle may be lifted, whereby, upon engagement of said presser foot with such stack, continued rotation of said screw will operate to lift said spindle to operate said switch to retract such armature, permitting manual operation of such lever to actuate such knife reciprocating mechanism.

3. In a power driven paper cutting machine including a knife adapted to be reciprocated to make a cut, and a hand lever adapted to be rocked to actuate drive mechanism for reciprocating such knife; a binder clamp adapted to clamp a stack of sheets or the like upon the table of such machine comprising a vertically disposed spindle, a screw on the lower portion of said spindle, a presser foot adapted to bear upon such stack threadedly engaging said screw for vertical reciprocation when said spindle and screw are rotated, means operative to drive said spindle,

stop means adapted to prevent rocking of such lever to actuate such knife drive mechanism, a solenoid operative when energized to retract said stop means, an electric circuit controlling said solenoid, a normally open switch in said circuit positioned to be operated by lifting of said spindle, and means limiting the distance said spindle may thus be lifted, whereby, upon engagement of said presser foot with such stack and firm clamping of the latter thereby, continued rotation of said screw will operate to lift said spindle to operate said switch to retract said stop, permitting manual operation of such lever to actuate such knife reciprocating mechanism.

4. In a power driven paper cutting machine including a knife adapted to be reciprocated to make a cut, and a hand lever adapted to be rocked to actuate drive mechanism for reciprocating such knife; a binder clamp adapted to clamp a stack of sheets or the like upon the table of such machine comprising a vertically disposed screw, a presser foot adapted to bear upon such stack threadedly engaging said screw for vertical reciprocation relative thereto when said screw is rotated, means operative to drive said screw, electrically controlled guard means normally operative to prevent rocking of such lever to actuate such knife drive mechanism, a switch operative when actuated to release said guard means to permit such rocking of such lever, said switch being positioned and arranged to be actuated by reciprocation of said screw, and means limiting the distance said screw may thus be reciprocated, whereby, upon engagement of said presser foot with such stack and firm clamping of the latter thereby, continued rotation of said screw will operate to lift the same to actuate said switch to release said guard means, permitting operation of such lever to actuate such knife reciprocating mechanism.

5. In a power driven paper cutting machine including a knife adapted to be operated to make a cut, and control means adapted to actuate drive mechanism for such knife; a binder clamp adapted to clamp a stack of sheets or the like comprising a screw, a presser foot adapted to bear against such stack threadedly engaging said screw for reciprocation relative thereto when said screw is rotated, means operative to drive said screw, electrically controlled guard means normally operative to prevent actuation of such drive mechanism for such knife, a switch arranged and disposed to be actuated by reciprocation of said screw and operative when thus actuated to release said electrically controlled

guard means, and means limiting the distance said screw may thus be reciprocated, whereby, upon engagement of said presser foot with such stack and firm clamping of the latter thereby, further rotation of said screw will serve to reciprocate the same to actuate said switch.

6. In a power driven paper cutting machine including a knife adapted to be operated to make a cut, and manual control means adapted to actuate drive mechanism for such knife; a binder clamp adapted to clamp a stack of sheets or the like comprising a screw, a presser foot adapted to bear against such stack threadedly engaging said screw for reciprocation relative thereto when said screw is rotated, means operative to drive said screw, guard means normally operative to prevent actuation of such control means for such drive means for such knife, and means responsive to lifting of said screw operative to release said guard means, whereby, upon engagement of said presser foot with such stack and firm clamping of the latter thereby, further rotation of said screw in the same direction will serve to lift the same to release said guard means.

7. In a power driven paper cutting machine including a knife adapted to be driven to make a cut, and drive mechanism for such knife; a binder clamp adapted to clamp a stack of sheets or the like including a presser foot, a screw threadedly engaging said presser foot for reciprocation of the latter, said screw being mounted for limited axial shifting away from such stack upon clamping engagement of said presser foot with the work with consequent cessation of such reciprocation of said presser foot, means adapted to drive said screw to reciprocate said presser foot at a slower rate than such knife drive mechanism is adapted to drive such knife, and means controlling initiation of movement of such knife responsive to such axial shifting of said screw when the work has thus been clamped to set up such knife drive mechanism for actuation.
